**MANDRELS AND OTHER WORK
 HOLDING MEDIA**
 Alfred E. Sykes, 329 Leicester Road,
 Markfield, Leicester, England
 Filed Nov. 30, 1965, Ser. No. 510,515
 5 Claims. (Cl. 269—20)

This invention relates to mandrels and other work holding media.

According to the present invention there is provided an expanding mandrel, including a relatively non-distortable substantially cylindrical reactor block having a central bore therein and a relatively distortable sleeve surrounding the reactor block, there being located within cylindrical bores disposed radially in the reactor block and communicating with the central bore at least three axial rows of thrust units, each thrust unit being capable of being urged by fluid pressure into contact with the inner wall of the sleeve, whereby on fluid pressure being applied to the thrust units the sleeve becomes distorted to increase its effective outside diameter.

In order that the invention may readily be carried into effect, two embodiments thereof will now be described, by way of example only, and with reference to the accompanying drawings, in which:

FIG. 1 is a cross-sectional view of a work holding device which incorporates an expanding mandrel in accordance with the present invention;

FIG. 2 is a cross-sectional view on the line II—II of FIG. 1;

FIG. 3 is a plan view of a further embodiment of work holding device which incorporates a plurality of expanding mandrels in accordance with the invention;

FIG. 4 is an end view of the device illustrated in FIG. 3; and

FIG. 5 is a section on the line V—V of FIG. 3.

Referring first of all to FIGS. 1 and 2 which show a work holding device particularly suitable for face grinding gears, an expanding mandrel in accordance with the present invention, generally indicated at 1, is mounted on an existing machine table 1a. The expanding mandrel 1 includes a relatively non-distortable reactor block 2 which, as will be seen more particularly from FIG. 2, is substantially cylindrical apart from flats 3 the purpose of which will be explained later. This reactor block 2 is made of steel or some other appropriate metal and is relatively non-distortable in relation to a relatively distortable sleeve 4 which surrounds the reactor block 2. The distortable sleeve 4 has an integral base 5 and may be of steel or other suitable metal and have a wall thickness which is capable of being distorted slightly under internal pressure from pressure areas. The base 5 is fixed by bolts 6 to a mandrel holder 7 fixed by bolts 8 to the machine table 1a and passing through an aperture 9 therein. Within the reactor block 2 is a central bore 10 which communicates via ducts 11 with a plurality of cylindrical bores 12 disposed radially in the reactor block 2, each of these cylindrical bores 12 housing a thrust unit 13 which may consist of a metal disc faced with a disc of a more resilient material, for example, neoprene. Each of the thrust units 13 is adapted to be urged radially outwardly of the reactor block 2 so as to contact the inner surface of the sleeve 4. The thrust units 13 are arranged in axial rows and there are at least three of said rows arranged symmetrically about the reactor block. In the particular embodiment shown in FIG. 1 there are four such rows, each arranged at a right angle to the adjacent rows as will be seen in FIG. 2. There should be at least two thrust units in each such row and, as will be seen from FIG. 2, in this particular embodiment there are four such thrust units in each such row.

2

Located within the central bore 10 is a primary piston 14 for increasing the fluid pressure within the system. This primary piston 14 is urged into its pressure applying position by a spring force and in this particular embodiment the spring force is given by a bank of Belleville washers 15 bearing at one end against a plug 16 which closes the lower end of the mandrel holder 7 and at the other end against a head 17 of an operating rod 18. The lower end of operating rod 18 is provided with a steel pin 19 which engages within recess 20 of a lever 21 pivoted at one end 22 to a bracket 23 fixed by bolt 24 to machine table 1a and having a roller 25 at its other end which co-operates with a cam track 26.

Communicating with central bore 10 is a further bore 27 within which is a secondary piston 28 which is manually operable.

The work holding device illustrated in FIGS. 1 and 2 is oil operated, and, as previously mentioned, is particularly suitable for face grinding gears and one such gear 29 is indicated, by chain-dotted line 29, in position on the mandrel 1. With oil pressure within the system at a minimum, no distortion will occur to the sleeve 4 and therefore the gear 29 may be slipped easily over the mandrel 1, the depth of entry of the mandrel 1 into the bore of gear 29 being governed by the position of a register bush 30. The oil pressure within the system is adjusted by means of the secondary piston 28 whereby thrust units 13 are forced radially outwardly against the inner surface of the deformable sleeve 4 but this pressure is not sufficient to distort the sleeve 4 but is merely a setting-up pressure. The actual gripping force will be supplied when roller 25 (which, in the setting up procedure and in positioning the work on the mandrel, has been in position 25a indicated by dotted lines) moves over the cam track 26 so that the roller assumes position 25. This releases the downward holding force on the operating rod 18 and, by virtue of the reaction in Belleville washers 15, the primary piston 14 is forced upwardly so as to increase the oil pressure within the system. This increase in pressure forces the thrust units 13 radially outwardly and it will be seen from FIG. 2 the sleeve 4 is distorted so that the effective outside diameter of the sleeve 4 is increased. It will be appreciated that in the axial areas where the rows of thrust units 13 are operating, lobes 31 will be formed and the parts of the sleeve 4 which are intermediate these lobes will move radially inwardly. This latter movement is allowed for by the flats 3 previously referred to on the outer surface of the reactor block 2. On roller 25 moving into position 25a once again, the operating rod 18 can move vertically downwards and the pressure exerted by primary piston 14 is relieved, thereby the sleeve 4 reverts to its original ring shape and the grip on the work is removed.

In the embodiment illustrated in FIGS. 3 to 5, a plurality of expanding mandrels are employed of the same general construction as described in relation to FIG. 1. These mandrels 1 are all mounted on a casing 32 and are supplied with oil pressure from a common pressure source 33 which may be a hand operated pump. Within the casing 32 are common pressure transmitting ducts 34 and also a pressure indicator 35 may be provided. The pressure indicator 35 may include a pin 36 which is moved for a given distance to assume the position shown in dotted line 36a when the locking pressure has been reached in the system. Two secondary pistons 37 and 38 may be provided for adjustment purposes only in the same way that secondary piston 28 was provided in the FIG. 1 embodiment. Also, a high pressure hydraulic plug 39 may be included in the system.

A detail of FIG. 3 is shown in FIG. 5 illustrating a gear 40 positioned on the mandrel 1 for face grinding.

It will be appreciated that with an expanding mandrel constructed in accordance with the present invention, because each of the thrust units is forced outwardly from a common pressure source, the distortion of the sleeve 4 will be equal at all points where pressure is exerted. Also, there are no places in the mandrel through which swarf or dirt may enter.

The construction of work holding device may be modified within the scope of the invention as defined in the appended claims, for example, instead of being oil operated, air or a liquid other than oil may be used as the pressure transmitting medium.

I claim:

1. An expanding mandrel, including a relatively non-distortable substantially cylindrical reactor block having a central bore therein and cylindrical bores disposed radially in the reactor block and communicating with the central bore, and a relatively distortable sleeve surrounding the reactor block, there being located within said radially disposed bores four axial rows of thrust units symmetrically disposed in the reactor block, each row consisting of four equally spaced thrust units; each thrust unit being capable of being urged by fluid pressure into contact with the inner wall of the sleeve, whereby on fluid pressure being applied to the thrust units, the sleeve becomes distorted to increase its effective outside diameter, the mandrel being further characterized in that the outer surface of the reactor block between the rows of thrust units is provided with flats to allow those parts of the distortable sleeve between the rows of thrust units to distort radially inwardly on the effective outside diameter of the sleeve being increased.

2. An expanding mandrel as claimed in claim 1, in which a primary piston for supplying working fluid pressure to the thrust units is located within the central bore of the reactor block, said primary piston being sprung urged to a pressure-applying position.

3. An expanding mandrel as claimed in claim 2, in which Belleville washers are employed to urge the primary piston to the pressure applying position, the Belleville washers being held compressed so that the primary piston is in the pressure relieved position by an operating rod.

4. An expanding mandrel as claimed in claim 2, in which located within a further bore which communicates with the central bore of the reactor block is a secondary piston manually operable for setting the fluid pressure within the central bore preparatory to the primary piston being operated.

5. In a work holding device, an expanding mandrel as claimed in claim 3, in which the operating rod is given axial movement by a lever arm having at one end a roller which engages a cam track.
